UNITED STATES PATENT OFFICE.

OSKAR MARTIN, OF NEW YORK, N. Y.

DESIGN FOR A DRAWER.

SPECIFICATION forming part of Design No. 19,244, dated July 30, 1889.

Application filed July 1, 1889. Serial No. 316,238. Term of patent 7 years.

To all whom it may concern:

Be it known that I, OSKAR MARTIN, a citizen of Germany, residing at New York, county and State of New York, have invented and 5 produced a new and original Design for a Drawer, of which the following is a specification, reference being had to the accompanying illustrations, forming part thereof.

Figure 1 is a face view of a series of my 10 newly-designed drawers, showing them in a spice-case. Fig. 2 is a section on line xx , Fig. 1, and Fig. 3 a perspective view of the drawer.

The leading feature of my design consists 15 in a drawer having a rectangular outline, an oval opening, and an ornamental button.

A A is a spice-case for containing a num-

ber of my newly-designed drawers c . This case may be provided with partitions b and beads a .

Each drawer c is made of square or rectangular shape or outline, with an oval opening.

The drawers are embellished by ornamental buttons d .

I claim as my invention—

The design for a drawer c , having a square outline, an oval opening, and an ornamental button d , substantially as shown.

OSKAR MARTIN.
